(57) **CLAIM**

The ornamental design for a combined charcoal briquette spreader and rake, as shown and described.

DESCRIPTION

FIG. 1 is a front perspective view of a combined charcoal briquette spreader and rake illustrating my new design;

FIG. 2 is top plan view thereof;

FIG. 3 is a bottom plan view thereof;

FIG. 4 is a left side elevation view thereof; the right side elevation view being identical thereto;

FIG. 5 is a front view thereof; and,

FIG. 6 is a rear view thereof.
